LADDER ASSEMBLING MACHINE

Ned L. Thrasher, Perrysburg, N. Y.

Application October 9, 1934, Serial No. 747,615

3 Claims. (Cl. 144—2)

The present invention relates to new and useful improvements in ladder assembling machines and has for its primary object to provide, in a manner as hereinafter set forth, a machine of this character embodying a novel construction, combination and arrangement of parts through the medium of which all of the rungs of the ladder may be expeditiously and simultaneously mounted in the side rails of said ladder.

Another important object of the invention is to provide an assembling machine of the aforementioned character which is adapted for use in assembling different types or shapes of ladders.

Other objects of the invention are to provide a ladder assembling machine which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a fragmentary view in top plan of a ladder assembling machine constructed in accordance with the present invention.

Figure 2 is a view in end elevation of the invention.

Figure 3 is a fragmentary side elevational view.

Figure 4 is a vertical sectional view, taken substantially on the line 4—4 of Figure 1.

Figure 5 is a sectional view, taken substantially on the line 5—5 of Figure 1.

Figure 6 is a sectional view, taken substantially on the line 6—6 of Figure 1.

Figure 7 is a detail view in elevation, looking at the outer side of the lower portion of one of the ladder engaging heads.

Figure 8 is a vertical sectional view, taken substantially on the line 8—8 of Figure 1.

Figure 9 is a detail view in section through one of the pressure screws, taken substantially on the line 9—9 of Figure 6.

Figure 10 is a view in vertical section through one of the cross members, taken substantially on the line 10—10 of Figure 1.

Figure 11 is a detail view in side elevation of one of the adjusting sleeves.

Figure 12 is a detail view in section through one of the adjusting sleeves, taken substantially on the line 12—12 of Figure 11.

Figure 13 is a detail view in side elevation of one of the ladder rail engaging brackets.

Figure 14 is a detail view in front elevation of one of the ladder rail engaging brackets.

Figure 15 is a detail view in top plan of one of the ladder rail engaging brackets.

Referring now to the drawings in detail, it will be seen that the embodiment of the invention which has been illustrated comprises a supporting structure or bench which is designated generally by the reference numeral 1. Mounted on the bench 1 are cross members or beams 2 having secured thereon strips 3 (see Figures 4 and 10), which refine T-slots 4.

Mounted longitudinally on the bench 1 are I-beams 5 and 6 which constitute bases for castings 7 and 8, respectively. Stationary screw shafts 9 are mounted for adjustment in the castings 7, said screw shafts 9 being secured in adjusted position by nuts 10 which are threaded thereon and which are engageable with opposite sides of said castings 7.

Extending slidably and adjustably through the castings 8 are screw shafts 11 which are threadedly mounted in sleeves 12 having fluted heads or flanges 13 on their outer ends. Mounted on the outer end portions of the sleeves 12, in abutting engagement with the outer ends of the castings 8, are worm gears 14 to which said sleeves are detachably secured through the medium of bolts 15 which pass through the flanges or heads 13. Keys 16 are mounted in chambers 17 in the castings 8 and engaged in keyways 18 in the pressure screws 11 for retaining said pressure screws against rotation. The inner end portions of the sleeves 12 have threaded thereon lock nuts 19, as best seen in Figure 8 of the drawings.

The sleeves 12 are further provided, on their inner ends, with thrust bearings 20.

Mounted in suitable bearings 21 is a shaft 22 having fixed thereon worm gears 23 which mesh with the gears 14. The shaft 22 is driven from an electric motor 24 through a belt and pulley connection 25.

Mounted on the inner ends of the pressure screws 9 and 11 are heads 26 which, as best seen in Figure 6 of the drawings are provided with sockets 27 which receive the unthreaded inner end portions of said pressure screws 9 and 11. Pins 28 secure the heads 26 to the pressure screws. The heads 26 include spaced guide plates 29 which travel in the T-slots 4. The heads 26 further include upper and lower flanges 30 and 31, respectively, between which angular ladder rail engaging and supporting brackets 32 are mounted for rocking adjustment in a hori-

zontal plane. Secured in the upper portions of the brackets 32, as by set screws 33, are threaded pins 34 which extend slidably through the upper flanges 11 and have threadedly mounted thereon adjusting and lock nuts 34'. The nuts 34' are provided with actuating handles or levers 35. Secured in the lower flanges 31 of the heads 26, as by set screws 36, are vertical guides 37 with which the brackets 32 are slidably engaged. The guides 37 extend below the flanges 31 into the guide plates 29 of the heads 26. Openings 38 are provided in the brackets 32 to accommodate the ends of the ladder rungs. In Figure 1 of the drawings, a portion of a ladder is shown mounted in the machine, the rungs of said ladder being designated by the reference numeral 39 and the side rails by the reference numeral 40.

Briefly, the manner of using the machine is as follows:—

The heads 26 are adjusted to the desired position on the bench and the side rails, with the ends of the rungs introduced into the openings provided therefor in said side rails, are mounted on the brackets 32. It will be understood that after the screws 9 are adjusted to the desired position, the heads 26 on said screw shafts 9 are stationary. The motor 24 is then energized to drive the shaft 22, thus driving the pressure screws 11 inwardly through the gears 23 and 14 and the sleeves 12. As is thought to be apparent, this operation drives the rail 40 of the ladder which is adjacent the pressure screws 11 toward the other ladder rail which is held stationary by the screw shafts 9, thus forcing the end portions of the ladder rungs into the openings provided therefor in said ladder rails.

The rockable mounting of the brackets 32 on the heads 26 permit said brackets to meet various conditions and facilitate the proper engagement of said brackets with different types or shapes of ladders. The adjustability of the screw shafts 9 and 11 also facilitates the use of the machine with different sizes, types or shapes of ladders. The screw shafts 11 are manually adjusted in the casings 8 by removing the bolts 15, thus permitting the sleeves 12 to be rotated for moving said screw shafts 11 inwardly or outwardly, as desired. The fluted heads or flanges 13 facilitate manual rotation of the sleeves 12.

It is believed that the many advantages of a ladder assembling machine constructed in accordance with the present invention will be readily understood, and although a preferred embodiment of the invention is as illustrated and described, it is to be understood that changes in

the details of construction and in the combination and arrangement of parts may be resorted to which will fall within the scope of the invention as claimed.

What is claimed is:—

1. A ladder assembling machine comprising a supporting structure, brackets on the supporting structure engageable with one side of a ladder, castings mounted on the supporting structure, sleeves journaled in the castings, shafts splined in the castings and threadedly engaged in the sleeves, brackets on said shafts engageable with the other side of the ladder, a drive shaft rotatably mounted on the supporting structure, means for actuating said drive shaft, and means operatively connecting the sleeves to the drive shaft for moving the second named brackets toward the first named brackets for clamping the ladder therebetween. 5

2. A ladder assembling machine comprising a supporting structure, brackets on the supporting structure engageable with one side of a ladder, castings mounted on the supporting structure, sleeves journaled in the castings, shafts splined in the castings and threadedly engaged in the sleeves, brackets on said shafts engageable with the other side of the ladder, a drive shaft rotatably mounted on the supporting structure, means for actuating said drive shaft, means operatively connecting the sleeves to the drive shaft for moving the second named brackets toward the first named brackets for clamping the ladder therebetween, the last named means including gears mounted on the sleeves, flanges on said sleeves detachably secured to the gears, and gears fixed on the drive shaft and operatively engaged with the first named gears, said flanges, when detached from the first named gears, constituting means for manually rotating the sleeves for adjusting the second named brackets. 10

3. A ladder assembling machine comprising a supporting structure, screw shafts mounted on said supporting structure, means on the screw shafts for clamping a ladder therebetween, said means including heads mounted on the screw shafts, opposed upper and lower flanges on said heads, brackets mounted for swinging movement between the flanges, and means for adjusting said brackets vertically between said flanges, said brackets being engageable with opposite sides of the ladder, and means for moving certain of the screw shafts toward and away from the ladder. 15
